ALFRED N. GOLDSMITH, OF NEW YORK, AND ARTHUR F. VAN DYCK, OF RYE, NEW YORK, ASSIGNEES TO RADIO CORPORATION OF AMERICA, A CORPORATION OF DELAWARE.

ELECTRICAL SIGNALING SYSTEM AND SIGNALING METHOD.

Application filed November 20, 1924. Serial No. 751,031.

Our invention relates to electrical systems and particularly to electrical signaling systems for the reception and detecting of signal waves by utilizing the principle of so-called 5 beats.

Heretofore in electrical signaling systems employing beat frequencies obtained by generating and combining suitable auxiliary frequencies with the signal waves certain disadvantages resulted which are as follows:

With the reception of desired signal waves of a given frequency a plurality of adjustments of the device supplying the auxiliary frequencies was possible for the production 15 of the desired beat frequencies. This naturally resulted in confusion to the operator of the system.

Also one particular adjustment of the device supplying the auxiliary frequencies resulted in the production of the desired beat frequency not only from the desired signal waves but from certain undesired waves as well. This resulted in interference.

One of the principal objects of our invention 25 is the provision of systems utilizing the beat frequency principle in which substantially only one adjustment of the device for generating the auxiliary frequency is possible for the production of the desired beat frequency from the signal waves.

Another principal object of our invention is the provision of a system utilizing the beat frequency principle in which with a certain 35 adjustment of the device for generating the auxiliary frequency, the desired beat frequency is produced only from the desired signal waves and not from certain undesired signal waves.

Another object of our invention is the simplification of the controls in such systems.

Other objects and advantages inherent in our invention will be apparent from the following description taken in connection with the accompanying drawings, in which:

Fig. 1 is a schematic diagram of a simple heterodyne system,

Fig. 2 is a schematic diagram of a simple autodyne system and

Fig. 3 is a schematic diagram of a combined autodyne and reflexing system.

Referring to Fig. 1, an antenna 1 is connected to ground G through the primary winding of the coupling device 2, the secondary winding of which is connected to

the input terminals of an electrical filter A. 55 A variable condenser 3 is connected in shunt with the secondary winding for properly tuning the antenna circuit to the incoming signal waves. The electrical filter A is of the low pass type and comprises a plurality 60 of reactance coils 4 connected in series and a plurality of variable condensers 5 connected in shunt as shown.

The output terminals of the filter A are connected to the input terminals of a detector device as shown.

The local oscillation generator is inductively coupled to one of the output leads of the filter A as shown. The output terminals of the detector device may be connected to 70 the sound reproductive device 6 through a plurality of audio frequency amplifiers as shown.

Referring to Fig. 2 an antenna 10 is connected to ground G through the primary 75 winding of a coupling device 11, the secondary winding of which is connected to the input terminals of electrical filter B. A variable condenser 12 is connected in shunt with the secondary winding for properly tuning 80 the antenna circuit to the incoming signal waves.

The filter B is of the low pass type and comprises a plurality of reactance coils connected in series and a plurality of variable 85 condensers 14 connected in shunt as shown.

The output terminals of filter B are inductively coupled to the combined detector and oscillation generator by means of the coupling device 15. The output terminals of the 90 detector and oscillation generator may be connected to the sound reproductive device 16 through a plurality of audio frequency amplifiers as shown.

Referring to Fig. 3 an antenna 20 is connected to ground G through the primary winding of inductive coupling device 21, the secondary winding of which is connected to the input terminals of an electrical filter C. A variable condenser 22 is shunted across 95 the secondary winding for properly tuning the antenna circuit to the incoming signal waves.

The filter C, which is of the low pass type, comprises a plurality of reactance coils 23 100 connected in series and a plurality of variable condensers 24 connected in shunt as shown. The output terminals of the filter C are con-

nected across the grid filament of 3-element tube 25 which serves as a radio frequency amplifier.

The plate of tube 25 is connected to the 5 grid of the combined oscillating and detecting tube 26 through a small blocking condenser 27' for preventing the impression of the B battery voltage of the plate filament circuit of tube 25 on the grid element of the 10 tube 26.

An inductance coil 27 is connected across the grid and filament of tube 26, a variable tuning condenser 28 being connected in shunt with the said coil. The plate filament circuit of tube 26 comprises the plate battery B₁, primary winding of beat frequency transformer 29 and a tickler coil 30 inductively coupled to the inductance coil 27, the battery B₁ with primary winding of beat frequency transformer 29 and the tickler coil 30 all being connected in series.

A condenser 31 is shunted across the primary winding of transformer 29 for bypassing the high frequency oscillations and 25 for tuning the transformer to the desired beat frequency and a blocking condenser 32 is so connected in one of the leads connecting one of the output terminals of the filter C to the grid of tube 25 as to prevent the intermediate frequency oscillations being impressed on the antenna and at the same time so connected as to be excluded from the antenna and filter circuits.

The secondary winding of beat frequency 35 transformer 29 is connected across the grid-filament of tube 25, the connection to the grid of tube 25 being made between the grid and the condenser 32. The plate-filament circuit of tube 25 also comprises the primary winding 40 of beat frequency transformer 33 and a B-battery both connected in series, the connection to the plate of tube 25 not including the condenser 27'. The secondary winding of beat frequency transformer 33 is connected 45 across the input terminals of the beat frequency amplifier.

The output terminals of the beat frequency amplifier are connected to the input terminals of the detector device as shown. The output 50 terminals of the detector device may be connected to a sound reproductive device 35 through a plurality of audio frequency amplifiers as shown.

The filaments of the various tubes may be 55 supplied with heating current from a suitable source of power A₁ and the currents in the individual filaments may be independently controlled by the various rheostats R.

In each of the systems shown by Figs. 1, 60 2 and 3 of the drawing, the antenna tuning condenser, the filter condensers and the oscillation generator are all preferably simultaneously controlled by a single control device as shown, thereby eliminating the disadvantage 65 of multiplicity of controls. However, we

do not limit ourselves to this single control arrangement, but may control the various variable elements in our systems separately or in various combinations.

Therefore, according to our preferred arrangement when the single control device is moved to a predetermined position the antenna circuit is tuned to signal waves of a certain frequency the cut-off point of the electrical filter is simultaneously adjusted to prevent 70 the passage of interfering waves and the oscillation generator is also simultaneously adjusted to generate an auxiliary frequency of the proper value to combine with the desired signal waves. 80

While we have shown and described low pass filters incorporated in our various systems we do not limit ourselves to filters of this type, but may employ high pass filters, band filters or various combinations of these 85 filters depending on the auxiliary frequency as compared with the frequency of the desired signal waves.

As the systems shown in Figs. 1 and 2 function in substantially the same manner, the 90 only difference being that one is of the heterodyne type while the other is of the auto-dyne type, a single description of the operation of both systems is thought to suffice.

Assume that the signal waves to be detected 95 possess a frequency of 600 kilocycles. The single control element is moved to a predetermined position which simultaneously tunes the antenna circuit to the 600 kilocycle signal waves, the oscillation generator circuit 100 to cause the generator to produce an auxiliary frequency of say 610 kilocycles and the electrical filter to prevent the passage of waves having a greater frequency than a value 105 slightly above the frequency of the signal waves, 600 kilocycles in this concrete example.

The 600 kilocycle signal waves and the 610 kilocycle auxiliary combine to produce 10 kilocycle beats, which are detected and amplified. It is thus apparent that the desired beat 110 frequency waves are only obtainable from signal waves of a certain frequency when the single control device occupies one predetermined position rather than a plurality of 115 positions when a separate control device is employed for the oscillation generator.

Assume now that undesired waves of a frequency of say 620 kilocycles impinge on the antenna. In systems heretofore used the antenna circuit could not be tuned sharply 120 enough to prevent its being influenced by these undesired waves. These waves would, of course, combine with the 610 kilocycle auxiliary waves to produce the 10 kilocycle beat waves. Interference was the result. In 125 our systems the electrical filter, having a cut-off point at a frequency slightly above the desired frequency, (600 kilocycles is the concrete example given) will prevent passage of these undesired waves and consequently they 130

will have no influence on the receiving circuit. Interference is thus eliminated.

In the concrete example given above, the oscillation generator might be arranged to 5 produce auxiliary waves of a frequency of 590 kilocycles which when combined with the desired signal waves of a frequency of 600 kilocycles would result in 10 kilocycle beat frequency waves. In this case a filter of the 10 high pass type would be employed for preventing the passage of waves having a lower frequency than the frequency of the desired waves (600 kilocycles). Undesired waves of say 580 kilocycles would then be prevented 15 from combining with the auxiliary waves of 590 kilocycles to produce the desired 10 kilocycle beat frequency waves. Interference would be similarly prevented in this case also.

The system shown in Fig. 3 functions as 20 follows:

The single control device is moved to a predetermined position which simultaneously operates, first: the condenser 22 to tune the antenna circuit to the frequency of the desired signal waves, second: the condenser 28 to properly tune the plate circuit of the oscillation generator 26 to cause it to generate auxiliary waves at a frequency equal to the frequency of the signal waves plus the frequency of the desired beat frequency waves 25 and third: the condensers 24 of the low pass filter C to properly tune the low pass filter C to prevent the passage of waves having a frequency greater than the frequency of 30 the desired waves.

The incoming signal waves are impressed on the grid filament of the radio frequency amplifying tube 25 where they are amplified. These oscillations are then impressed on the 40 grid of the combined oscillating and detecting tube 26. By means of the tickler coil 30 and the proper adjustment of the variable condenser 28, as described above, the tube 26 is made to produce auxiliary waves of a frequency equal to the frequency of the incoming signal waves plus the desired beat frequency waves.

Owing to the fact the inductance coil 27 and variable condenser 28 are connected 50 across the grid and filament of the tube 26 the incoming signal waves will be impressed on the grid of tube 26 and no diminution, but in fact magnification of the potential on the grid, will result because the condenser 28 is 55 adjusted to make the coupling comprising inductance 27 and condenser 28 substantially resonant to the incoming signal waves.

The beat frequency waves appearing in the plate-filament circuit of tube 26 are now impressed on the grid and filament of tube 25 60 by means of the beat frequency transformer 29, the condenser 31 by-passing all the high frequency oscillations and also serving to tune the plate filament circuit of tube 26 to 65 the desired beat frequency waves. The beat

frequency waves, considerably amplified by tube 25, will now appear in the plate filament circuit of tube 25, in which is included the primary winding of beat frequency transformer 33, the secondary winding of which is 70 connected to the input terminals of the beat frequency amplifier as shown.

The output terminals of the beat frequency amplifier are connected to the input side of the detector in which the beat frequency oscillations are detected. The audio frequency oscillations appearing in the output side of the detector are now impressed on the sound reproductive device 35 through a plurality 75 of audio frequency amplifiers as shown.

As explained above in connection with the systems shown by Figs. 1 and 2, the electrical filter C, may be of the high pass type, low pass type, the band type, or a combination 80 of these various types of filters depending on the desired relationship of the frequency of the auxiliary waves to the frequency of the signal waves to be detected.

While we have shown and described various modifications of our invention we do not 85 limit ourselves to said modifications, but may employ such other embodiments as may come within the spirit and scope of our invention.

Having described our invention, what we 90 claim is:

1. The combination of an input circuit responsive to waves, adjusting means for tuning said circuit, electrical filter means cooperating with said input circuit and permitting only the passage of desired signal waves 95 of certain predetermined frequencies, adjusting means for tuning said filter, means for producing beat frequency waves from the desired signal waves, adjusting means for said beat producer and a single control device for simultaneously actuating the said adjusting means of said input circuit, said filter means and said beat frequency producing means.

2. The combination of an input circuit responsive to waves, adjusting means for tuning said circuit, electrical filter means cooperating with said input circuit, adjusting means for tuning said filter circuit, means for producing oscillations, adjusting means for controlling the frequency of said oscillations and a single control device for simultaneously actuating the said adjusting means, said input adjusting means and said oscillator adjusting means being cooperatively arranged to give a constant super-audible local frequency and said input, oscillator and filter circuits being arranged to be cooperatively 105 tuned by said control member to cause the input and filter to admit a desired frequency and to cause said filter to exclude an undesired frequency which differs from the oscillator frequency by substantially the same amount as the oscillator differs from the desired signal.

3. In a super-heterodyne receiver, the com- 115 120 125

bination of a variably tuned input circuit, a variably tuned oscillator circuit for generating a beat frequency, a tuned intermediate frequency circuit for amplifying the 5 beat frequency and a tuned filter circuit, said last mentioned circuit being adapted to filter the input of the receiver and prevent an undesired frequency being passed which would, in combination with the oscillator frequency, 10 produce a beat frequency adapted to be passed by said intermediate frequency circuit.

4. In a super-heterodyne receiver, the combination of an input circuit, a variable condenser for tuning said circuit to the frequency 15 being received, an oscillator circuit for generating the beat frequency, a variable condenser for varying the frequency of the oscillator circuit, an intermediate frequency circuit 20 for amplifying the beat frequency and a filter circuit including a plurality of condensers for varying the frequency, which the said filter circuit is adapted to filter and prevent an undesired frequency being passed 25 which would, in combination with the oscillator frequency, produce a beat frequency amplifiable by said intermediate frequency circuit.

5. In a super-heterodyne receiver, the combination of an input circuit, a variable condenser for tuning said circuit to the frequency 30 being received, an oscillator circuit for generating a beat frequency, a variable condenser for varying the frequency of the oscillator circuit, a tuned intermediate frequency circuit, a filter circuit comprising a plurality of condensers for varying the frequency which the said filter circuit is adapted 35 to filter and prevent undesirable signals being passed, which would, in combination with the oscillator frequency, produce a beat amplifiable by said intermediate circuit and a single control device for simultaneously varying all of said condensers and therefore 40 the frequency to which the receiver is set to receive.

6. In a heterodyne radio receiving apparatus, a combination of an input circuit, a variable condenser for tuning said circuit, a 50 vacuum tube oscillator for generating beat frequency, a variable condenser for determining the frequency of said oscillator, a filter circuit between said input circuit and said oscillator, a variable condenser for determining the tuning of said filter circuit and a 55 single control device for simultaneously varying all of said condensers, the capacity of said input and filter condensers being adjustable by said control member for maintaining like tuning throughout their range, whereby beats from undesirable signals are 60 prevented and re-radiation of beat frequency is prevented and said oscillator condenser being controlled throughout its range by said 65 controlling member to tune said oscillator to

a constant difference frequency with respect to the tune of the input and filter circuits.

7. The method of preventing signal interference in a superheterodyne set comprising an input circuit, an oscillator circuit and a 70 selective absorption circuit, by a second materially different frequency which would heterodyne with the oscillator frequency to give the same beat frequency as that between the desired signal frequency and the oscillator 75 frequency which consists in tuning the input to the desired frequency and simultaneously tuning the absorption circuit in such electrical relation to said input circuit that said second frequency is removed. 80

8. In a radio receiving system the combination of means responsive to desired signal waves, adjustable means for producing auxiliary waves adapted to combine with said desired waves to produce a beat frequency, 85 adjustable means for permitting only the passage of desired signal waves of certain predetermined frequencies and a single control device for simultaneously tuning each of the last-mentioned adjustable means. 90

9. A radio receiving system comprising means for tuning its input, adjustable means for reducing a desired signal frequency simultaneously with a materially different interfering frequency to the same lower frequency, 95 variable means for removing the undesired frequency and means common to the three above mentioned means for varying them simultaneously. 100

10. In a radio receiving set utilizing the beat note method of signal reception, employing an input circuit, an oscillator circuit and a frequency selective impedance associated with the input circuit, the method of reducing interference which consists in tuning the 105 frequency selective impedance and the input circuit to different frequencies, each of these frequencies differing from that of the oscillator circuit by the same amount, and maintaining the above stated frequency relation 110 of the two circuits and the frequency selective impedance throughout the range of the set. 110

11. A signal responsive system comprising an input circuit including tuning means, an oscillator circuit including tuning means, a 115 filter circuit including tuning means, means for mechanically coupling said tuning means for simultaneous adjustment to maintain constant the difference of the input and oscillator circuit frequencies and to maintain the filter circuit so tuned as to filter out an undesired frequency which differs from the frequency of the oscillator circuit by an amount equal to half the difference between said undesired frequency and the frequency of said input circuit. 120

12. In a signal responsive system comprising an input circuit with tuning means, an oscillator circuit including tuning means, an absorption circuit including tuning means 125

- and an intermediate frequency amplifier, the method of eliminating interference which consists in tuning the input circuit to the desired signal frequency, tuning the oscillator 5 circuit for a frequency differing from that of the input circuit by the frequency for which the intermediate frequency amplifier is designed, tuning the absorption circuit for a frequency different from that of the input 10 circuit, and differing from that of the oscillator circuit by the frequency of the intermediate frequency amplifier, and maintaining the above stated frequency relation of the three circuits throughout the range of the 15 system.
13. A signal responsive system comprising an input circuit including tuning means, a filter circuit having a plurality of variable reactances, and means simultaneously to vary 20 said tuning means and said reactances, whereby to maintain a predetermined relationship between the frequency to which said input circuit is tuned and the frequencies to which said filter circuit is responsive.
14. A signal responsive system comprising an input circuit including tuning means, a filter circuit having a plurality of variable reactances connected to said input circuit, said filter being designed to pass only a pre- 25 determined range of electrical frequencies, and means simultaneously to vary said first mentioned tuning means and the variable reactances.
15. A radio receiver comprising in combi-
- nation, an input circuit, variable means to 35 tune said input circuit, an absorption circuit connected to said input circuit, said absorption circuit comprising a plurality of variable reactances, a local oscillation generator, means variably to tune said oscillation generator, and single means simultaneously to 40 vary both said tuning means and said variable reactances.
16. In a radio receiver having an input circuit, means to tune said input circuit, a filter connected to said input circuit, said filter having a variable tuning means, a local oscillation generator coupled to said filter, means to tune said local oscillation generator, and single means to vary all of said tuning 45 means.
17. In a radio receiver utilizing the beat note method of signal reception, a tuned antenna circuit, means to vary the tuning of 50 said circuit, a filter connected to said circuit, said filter being provided with a plurality of variable reactances, said circuit and said filter being tuned to two frequencies which differ from each other by a predetermined amount, and means simultaneously to vary 55 said first mentioned means and said variable reactances, whereby to maintain said predetermined frequency differences for various settings of the said first mentioned tuning means.
